UNITED STATES PATENT OFFICE.

LUCIUS E. WHITON, OF NEW LONDON, CONNECTICUT.

PROTECTION OF SHIPS AGAINST TORPEDO ATTACKS.

1,369,586.

Specification of Letters Patent. Patented Feb. 22, 1921.

Application filed May 25, 1917. Serial No. 170,847.

To all whom it may concern:

Be it known that I, LUCIUS E. WHITON, a citizen of the United States of America, residing at New London, Connecticut, have 5 invented a new and useful Protection of Ships Against Torpedo Attacks, of which the following is a specification.

Many different forms of devices have been proposed for preventing torpedoes from 10 reaching ships. It has been proposed to suspend nets and plates from the sides of the ship, but all of the constructions heretofore known, so far as I know, seriously impede the progress of the ship and are extremely 15 difficult to handle. It has also been proposed to provide auxiliary ships for towing devices for other ships. This of course still leaves the towing ship exposed and interferes with the independent operation of 20 ships.

It is my main object to provide a construction by which the ship itself can tow its own protecting means, such protecting means to be of such a nature as to interfere 25 as little as possible with the ordinary handling and movement of the ship, and to be of such a construction as to be relatively inexpensive and quickly and easily made of materials which can readily be returned to 30 commercial uses when not required as protectors.

In the preferred form, protection is afforded by a plurality of series of independent plates supported by trains of floats. The 35 plates are preferably suspended some distance below the floats so as to be positioned to receive the impact of torpedoes and cause the explosion at a distance from the side of the ship. Preferably, a space intervenes between 40 the plates and the floats so as to permit surface water to pass back and forth without disturbing the plates. Preferably the plates are arranged in two trains at each side of the ship, one train being in advance 45 of and farther from the ship than the other so as to permit the water currents thrown off from the bow of the ship to pass between the trains of plates with a minimum amount of interference and a minimum amount of 50 disturbance of the plates and impedance of the ship. The ship is preferably provided with a system of spars, stays and cables for towing these trains of floats and plates at

the proper distance from the ship. A similar set of spars, stays and cables are also 55 provided at the stern for handling the floats and plates when the ship is reversed and also for the purpose of keeping a connection with the floats and plates in case the trains are broken. 60

Figure 1 is a plan view more or less diagrammatic illustrating a ship with my invention applied.

Fig. 2 is a side view of the same.

Fig. 3 is a detail of one of the floats and 65 one end of an adjacent float and the suspended plates.

Fig. 4 is an end view of one of the floats and plates showing also in dotted lines the permissible relative movement between the 70 plate and the float.

10 is a stiff spar or boom near the water-line in the nature of a bowsprit having its forward end quite low down. 11 is a stiff spreader at the base of the bowsprit 10. 75 Cables, rods or ropes 12—12' connected to the ship extend around the ends of the spreader to the end of the bowsprit to stay it against stresses in a horizontal plane. Cables, rods, ropes or stays 13—13' extend 80 from the bow of the ship to the tip of the bowsprit to stay it against stresses in a vertical plane.

The towing booms 14—14' extend diagonally forward and outward from the bow of the ship. These are stayed against stresses in a horizontal plane by upwardly inclined rods, ropes or cables 15—15' extending from the ship to the outer ends of the booms, and downwardly inclined rods, ropes or cables 15—15^a and 15^b connecting the outer ends of the booms with the forward end of the bowsprit. These booms are also stayed against stresses in a vertical plane by rods, ropes or cables 16—16', extending from the bow of the ship to the outer ends of the booms. The stays 16 and 16' may pass directly to the bow or over a vertical support 17 with an anchor stay 16^b. The booms and bowsprit will, of course, be seated against suitably strong parts of the ship and they may be mounted so as to be dismantled readily or so as to be swung inwardly or upward in the manner of derrick masts and rigging. 100

105 Each protective train is made up of a series of floats 20—20 and plates 21—21.

These floats may be made of ordinary metal pipe such as spiral riveted pipe or even range boilers of suitable size to sustain the desired load. The plates may be ordinary 5 commercial plates of say $\frac{3}{16}$ in. thickness, and require no fabrication except at the suspension points. Preferably, the plates are suspended from the floats by links 22-22 so that the plates are spaced some little distance 10 below the floats to allow surface water and waves to pass over and around the floats and above the plates without interfering with the plates. These links may be hingedly connected to the floats and plates for instance by straps 23 and brackets 24. Preferably, a number of plates are independently supported from each float so as to facilitate handling, reduce fabrication, and permit the 15 passage of water currents without unnecessary impedance. Preferably, the floats are normally loosely connected together as at 25 so as to permit relative freedom of movement without straining the parts. The inner train, floats and plates, is towed by cable 26 20 passing around the sheave or pulley 27 and connected to a windlass 28 on the ship so that the train may be moved forward or backward into the desired position. The stern of the ship is preferably provided with 25 a system of booms, stays and cables similar to the bow and the rear end of the inner train may be connected to the ship by a cable 29 which is normally slack. The outer forward train is towed by a cable 30 passing 30 around a sheave or pulley 31 and connected to a windlass 32 on a ship, the rear of this outer train is also preferably provided with a cable 33 connected to the stern of the ship. This arrangement permits the water currents 35 thrown off from the bow of the ship to pass outward between the outer and inner trains of plates and floats with a minimum impedance and minimum interference with the plates. Fig. 1, in dotted lines, shows the forward outer train as thrown outward by 40 water currents. It will be obvious that this construction permits the forward and aft adjustment of the two trains relatively to each other and relatively to the ship so as 45 to bring them into the position which best corresponds with the speed of the ship and the water currents produced by the movement. This permits the application of the 50 towing forces as nearly as possible in true alignment with the direction of the ship.

The particular design and arrangement of the towing booms, cables, etc., will vary, of course, with the size and shape of the ship and the stresses which the protective plates 55 and floats produce. It is preferred as before indicated, that the booms and stays be so arranged as to afford the minimum impedance to the ship's speed and the maximum strength in the direction in which the 60 forces are applied, namely, the longitudinal

towing effect and the vertical stress resulting from the necessary downward pull as well as the pitching and rolling action of the ship.

It will be seen that the protective effect 70 of the construction and arrangement herein shown is wholly independent of the rolling or pitching of the ship to which attachment is effected only by the towing connection. By the arrangement shown, the outer train 75 which necessarily has the shorter towing line is shorter in length than the inner train and therefore produces a minimum stress.

If desired, the cross stays 15^a and 15^b may be arranged to carry suspended bars 35 80 adapted to detect and explode mines in the ship's path, or deflect or explode torpedoes approaching from forward angles.

I claim:

1. Apparatus for protecting a ship from 85 torpedoes comprising independently floating trains of protective members and means for towing said trains in pairs parallel to the ship with one train of each pair in advance of and outside of the other train of said pair so as to permit water currents from the bow of the ship to pass between the two trains of each pair of trains.

2. Apparatus for protecting a ship against torpedo attack comprising pairs of 95 inner and outer trains of protecting plates, floats for suspending said plates, means for towing said trains of plates independently of each other, with one train of each pair in advance of and outside of the other 100 train of said pair.

3. Apparatus for protecting a ship against torpedo attack comprising pairs of inner and outer trains of protecting plates, floats for suspending said plates, means for 105 towing said trains of plates independently of each other, with one train of each pair in advance of and outside of the other train of said pair, and means for adjusting the longitudinal position of the two trains 110 of each pair independently of each other.

4. Apparatus for protecting a ship against torpedo attack comprising pairs of inner and outer trains of protecting plates, floats for suspending said plates, means for 115 towing said trains of plates independently of each other, with one train of each pair in advance of and outside of the other train of said pair, and cables connecting the rear ends of said trains to the ship, said cables 120 being normally slack.

5. Apparatus for protecting a ship against torpedo attack comprising trains of floats at each side of the ship flexibly connected together and plates independently 125 suspended from said floats, and means for towing said trains at each side of the ship substantially parallel with the axis of the ship and with certain trains in advance of other trains.

6. Apparatus for protecting a ship against torpedo attack comprising a train of flexibly connected floats, a series of relatively imperforate vertically extending plates supported to swing from each float with a space between the floats and the plates, and a towing boom extending from the ship and a cable leading therefrom to said train of floats whereby the floats and

plates are towed by the ship itself and are 10 supported entirely by the water independently of the ship, said plates being adapted to resist relative lateral movement in the water, the space between the floats and the plates permitting the passage of surface water.

LUCIUS E. WHITON.
